BEDPAN

**Frank E. Jones, West Lafayette, Ohio, assignor to The
Jones Metal Products Company, West Lafayette, Ohio,
a corporation of Ohio**

Application April 22, 1953, Serial No. 24,619

Term of patent 14 years

(Cl. D83—1)

To all whom it may concern:

Be it known that I, Frank E. Jones, citizen of the United States, residing at West Lafayette, county of Coshocton, and State of Ohio, have invented a new, original, and ornamental Design for a Bedpan, of which the following is a specification, reference being had to the accompanying drawing, forming part thereof.

In the drawings, Fig. 1 is a top plan view of a bedpan embodying my new design; and Fig. 2 is an end view of the bedpan as viewed from the right in Fig. 1.

The characteristic feature of my design for a bedpan resides in the rear centrally disposed depressed portion having the configuration as shown.

I claim:
The ornamental design for a bedpan, as shown and described.
